(57) **CLAIM**

The ornamental design for a surgical implant extraction jaws set, as shown and described.

DESCRIPTION

FIG. 1 is a side view of a surgical implant extraction jaws set in accordance with my new design in an operative position; FIG. 2 is a perspective view of the upper one of the surgical implant extraction jaws set of FIG. 1 shown removed from the set for ease of illustration;

FIG. 3 is a right side view of the surgical implant extraction jaws set of FIG. 2;

FIG. 4 is a left side view of the surgical implant extraction jaws set of FIG. 2;

FIG. 5 is a front view of the surgical implant extraction jaws set of FIG. 2;

FIG. 6 is a rear view of the surgical implant extraction jaws set of FIG. 2;

FIG. 7 is a top view of the surgical implant extraction jaws set of FIG. 2;

FIG. 8 is a bottom view of the surgical implant extraction jaws set of FIG. 2;

FIG. 9 is a perspective view of the lower one of the surgical implant extraction jaws set of FIG. 1 shown removed from the set for ease of illustration;

FIG. 10 is a right side view of the surgical implant extraction jaws set of FIG. 9;

FIG. 11 is a left side view of the surgical implant extraction jaws set of FIG. 9;

FIG. 12 is a front view of the surgical implant extraction jaws set of FIG. 9;

FIG. 13 is a rear view of the surgical implant extraction jaws set of FIG. 9;

FIG. 14 is a top view of the surgical implant extraction jaws set of FIG. 9; and,

FIG. 15 is a bottom view of the surgical implant extraction jaws set of FIG. 9.

(Continued)

In the drawings, the dashed broken lines shown in FIGS. 1-15 illustrate portions of the surgical implant extraction jaws set that form no part of the claimed design.

The dash-dot broken lines shown in FIGS. 1-4, 7-11 and 14-15 illustrate the bounds of the claim and form no part of the claimed design.

1 Claim, 13 Drawing Sheets
